TABLE WITH ADJUSTABLE CANTILEVER SHELF

Nils Tage Olofsson, Lamhult, Sweden

Application November 28, 1949, Serial No. 129,721

Claims priority, application Sweden
August 22, 1949

6 Claims. (Cl. 311—40)

1
This invention relates to a combination night stand and table with an adjustable cantilever shelf.

The invention relates broadly to a night stand having a slidable supporting plate at one end for a shelf, which supporting plate may be latched in one of several selected positions, and a shelf pivotally connected to the supporting plate and arranged to function in one position as a table top and in another position as a top for the night stand.

The object of the invention is to provide a combination night stand and table which is readily convertible to use as a table but which has the appearance only of a night stand when not being used as a table.

Another object of the invention is to provide several forms of supporting and latching means for holding the supporting plate and shelf in position.

Other objects, advantages and improvements will become apparent from the following specification taken in connection with the accompanying drawings, in which:

Figure 1 is a perspective view of the combination night stand and table with the pivoted shelf extended to form a table;

Figure 2 is a view similar to Figure 1 but with the shelf folded over to form a top for the night stand;

Figure 3 is a side elevation view, partly in section, of a sub-modification of a supporting brace and latching means therefor for use with the shelf in the construction according to Figures 1 and 2;

Figure 4 is an end elevation view of a modified form of latching means for the lower end of the supporting brace; and,

Figure 5 is a side elevation view of the modified form of latching means for the supporting brace, as shown in Figure 4.

Referring now to the drawings in detail and to Figure 1 in particular, the combination night stand and table according to the present invention has a bottom 10, which telescopically receives an extension bottom plate 11 for a purpose which will appear hereinafter. The bottom 10 and extension bottom plate 11 are mounted on rollers or casters 12, three of these being shown but the exact number being immaterial. The cabinet of the combination night stand and table is comprised principally by four corner frame members 13. The top 15 of the cabinet, also forming a shelf, is mounted in horizontal position between the four corner frame members 13. The cabinet has a left wall 16 (Fig. 1) be-

tween the left corner frame members 13—13. It will be understood that there is a complementary right wall (not shown) between the right corner frame members 13—13. A door 20 comprises the front of the cabinet, being mounted on the right corner frame member 13 by hinges 19—19. The door has a pull ring 21 thereon. It will also be understood that the cabinet has a back wall (not shown) between the rear corner frame members 13—13, complementary to the door 20. Above the top 15 of the cabinet there is a frame comprised by side members 22—22 and end members 23—23. (Only one end member 23 is shown in Figure 1.) An auxiliary top 25 is mounted in horizontal position between the four corner frame members 13 and the side frame members 22—22 and end frame members 23—23. Between the left corner frame members 13—13 there is mounted a supporting plate 26 for vertical sliding movement in parallel relationship to the left end wall 16 of the cabinet. This supporting plate 26 is mounted in guideways comprising opposed longitudinally extending, centrally positioned grooves 14 in the left corner frame members 13. Aligned with the auxiliary top 25 there are lugs 18—18 mounted on the corner frame members 13—13. The supporting plate 26 is provided with stops 28—28 adjacent its opposite edges, which stops abut the lugs 18—18 to prevent the supporting plate from being pulled entirely out of position in the grooves 14 of the corner frame members 13.

The table shelf 30 is pivotally mounted on the top edge of the supporting plate 26 by hinges 29—29. A supporting brace 34 is provided for maintaining the table shelf in horizontal position. This brace has an upper end 33, which is bent at an obtuse angle to the axis of the brace and a lower end 35, which is also bent at an obtuse angle to its axis, the projected lines of the two ends being at a right angle to each other. The upper end 33 of the supporting brace is adapted to enter a hole 31 in the table shelf 30 and the lower end is adapted to pass through a hole 27 in the supporting plate 26 and enter one of a series of spaced holes 17 in the left end wall 16 of the cabinet.

It will be apparent that the supporting plate 26 may be slid upwardly, the table shelf 30 swung outwardly to the horizontal position and the supporting brace inserted with its upper end 33 in the hole 31 in the table shelf and its lower end 35 in the hole 27 in the supporting plate and one of the holes 17 in the left end wall 16 of the cabinet. Conversely, the supporting brace 34 may be removed and the table shelf 30 swung

through 180 degrees to overlie the auxiliary top 25 of the cabinet, as shown in Figure 2.

When the table shelf 30 is swung to the outward horizontal position of Figure 1, the extension bottom plate 11 may be moved outwardly to position the center of gravity of the table shelf 30 between the rollers 12 on the extension bottom plate and those on the main bottom plate 10. As so positioned, any tendency of the weight of the table shelf 30, in addition to the weight of any articles placed thereon, to tilt the entire structure is counteracted.

A book support 36 may be provided, if desired. This book support has an outwardly and upwardly extending flange 37 on its bottom and an inverted U-shaped bracket 38. The bracket 38 has outwardly directed toes (not shown), which are adapted to extend into spaced holes 32 in the table shelf 30.

In the modification of Figure 3 the arrangement of the slidable supporting plate 26" and table shelf 30" is similar to that in Figures 1 and 2. Hinges 51 are mounted on the edge of the slidable supporting plate 26" and the table shelf 30" could be used, if desired, as in the modification of Figures 1 and 2. The supporting brace 34" has at its upper end an obtuse angle section 58 and at its lower end a parallel but oppositely extending obtuse angle section 61. The upper obtuse angle section 58 of the supporting brace is mounted within a slot 60 in the table shelf 30" and pivotally secured to the latter by a pin 59 positioned in the side walls of the slot. Similarly, the lower obtuse angle section 61 of the supporting brace is pivotally secured at 62 between a pair of ears 63 on the slidable supporting plate 26". A pin 65 is pivotally secured at 64 to the outer end of the lower obtuse angle section 61 of the supporting brace. With the table shelf 30" in the horizontal position the pin 65 projects through the hole 27" in the slidable supporting plate 26" and into the hole 17" in the side wall 16" of the cabinet to secure both the slidable supporting plate and the table shelf in position. With the table shelf 30" raised to the vertical position, as shown in dotted lines in Figure 3, the pin 65 will be withdrawn from the hole 17" in the side wall 16" of the cabinet and into the hole 27" in the supporting plate 26" to permit vertical slidable movement of the latter along the side wall 16" of the cabinet. A plurality of vertically spaced holes 17" in the side wall 16" of the cabinet may be provided so that the shelf 30" may be positioned at corresponding selected levels, as in the modification of Figures 1 and 2.

The latching means for the supporting brace as shown in Figures 4 and 5 is also adapted to be used with the night stand and table in the modification according to Figures 1 and 2. A supporting plate 66 is mounted on the side wall 16" of the cabinet by screws 67. The lower end of the supporting brace 34" is formed as an obtuse angle section, in the same manner as the obtuse angle section 48 in the modification according to Figure 3. A plurality of vertically spaced stop members are each comprised by an upper long arm section 69 and a lower short arm section 71, attached at their apex to a pin 70 which extends between parallel ears 72. This construction of the latching means has the advantage that the table shelf in the horizontal position may be shifted upwardly or downwardly without being disturbed from such position. As the table shelf is moved upwardly the lower end 68

of the supporting brace 34" will trip over the upper ends 69 of the stop members, rotating each one successively toward the side wall 16" of the cabinet. After the lower end 68 of the supporting brace has passed by, the stop members will return to their original positions due to the weight of the long arm section 69 being greater than that of the short arm section 71 of each stop member. In order to lower the table shelf, it is only necessary to trip the successive stop members inwardly to a position with the long arm section 69 parallel to the cabinet wall 16" by pressing outwardly on the short arm section 71.

Having now fully described my invention, what I claim as new and useful and desire to secure by Letters Patent of the United States is:

1. A night table comprising a stand, parallel vertically positioned guideways on said stand, means positioned between said guideways forming a series of vertically spaced stops, a slidable plate mounted in said guideways and having at least one hole therein registrable with said vertically spaced stops, a table shelf pivotally mounted on said slidable plate, and a brace mounted beneath said table shelf for supporting the same, said brace having one end selectively insertable through the hole in the slidable plate in close fitting relationship and in selective engagement with one of said vertically spaced stops.

2. A night table comprising a stand, parallel vertically positioned guideways on said stand, a side wall mounted on said guideways and having a plurality of vertically spaced holes therein, a slidable plate mounted in said guideways and having at least one hole therein registrable with said vertically spaced holes, a table shelf pivotally mounted on said slidable plate, and a brace mounted below and in pivoted engagement with said table shelf for supporting same and having one end insertable in the aligned holes in the slidable plate and back wall.

3. A night table comprising a stand, parallel vertically positioned guideways on said stand, inwardly projecting lugs on said guideways, a side wall mounted on said guideways and having a plurality of vertically spaced holes therein, a slidable plate mounted in said guideways and having at least one hole therein selectively registrable with said vertically spaced holes, at least one pin on said slidable plate cooperable with said inwardly projecting lugs to limit sliding movement of said plate in said guideways, a table plate pivotally mounted on said slidable plate, and a brace positioned beneath said table plate for supporting the table plate and having one end selectively insertable in aligned holes in the slidable plate and back wall.

4. A night table comprising a stand, parallel vertically positioned guideways on said stand, a side wall mounted parallel to said guideways and having a series of vertically spaced stops mounted thereon, a slidable plate mounted in said guideways and having at least one hole therein selectively registrable with said vertically spaced stops, a table shelf pivotally mounted on said slidable plate, and a brace pivotally connected at one end to said table shelf and having its other end selectively insertable in the said hole in the slidable plate and selectively engaged by one of said stops on the side wall.

5. A night table comprising a stand, parallel vertically positioned guideways on said stand, a side wall mounted parallel to said guideways and having a series of vertically spaced stops

mounted thereon, a slidable plate mounted in said guideways and having at least one hole therein selectively registrable with said vertically spaced stops, a table shelf pivotally mounted on said slidable plate and having a longitudinally extending groove thereon, a brace pivotally connected at one end to the table shelf within said groove and pivotally connected at the other end to said slidable plate, said brace having an extension at an obtuse angle thereto beyond said last mentioned pivotal connection, and a pin on said extension insertable through the said hole in the slidable plate and for engagement with said stops when the table shelf is at right angles to the slidable plate and to be withdrawn from said hole and engagement with said stop when the table shelf is in alignment with the slidable plate.

6. A night table comprising a stand, parallel vertically positioned guideways on said stand, a side wall mounted parallel to said guideways and having a series of vertically spaced swingable stops mounted therein, a slidable plate mounted in said guideways and having at least one hole therein selectively registrable with said vertically spaced stops, a table shelf pivotally mounted on

said slidable plate, and a brace pivotally connected at one end to said table shelf and having its other end insertable in the said hole in the slidable plate to be selectively engaged by one of said stops on the back wall to prevent downward movement while freely permitting upward movement of said table shelf, slidable plate and brace.
